[57] **CLAIM**

The ornamental design for a rotary stand for potted plants, as shown and described.

DESCRIPTION

FIG. 1 is a perspective view of a rotary stand for potted plants embodying my new design;

FIG. 2 is a top plan elevational view thereof.

FIG. 3 is a side elevational view thereof.

The bottom of the stand is a plane surface.

FIG. 1

FIG. 2

FIG. 3
